(57) CLAIM

I claim the ornamental design for a beauty products organizer, as shown and described.

DESCRIPTION

FIG. 1 is a front perspective view of a beauty products organizer, showing my new design;

FIG. 2 is an exploded front perspective view thereof;

FIG. 3 is an exploded rear perspective view thereof;

FIG. 4 is a front elevational view of FIG. 1;

FIG. 5 is a rear elevational view of FIG. 1;

FIG. 6 is a right-side elevational view of FIG. 1;

FIG. 7 is a left-side elevational view of FIG. 1;

FIG. 8 is a top plan view of FIG. 1; and,

FIG. 9 is a bottom plan view of FIG. 1.

The broken lines showing beauty products in FIG. 1 depict environmental matter and form no part of the claimed design.
